UNITED STATES PATENT OFFICE.

JAMES SAMUEL KING, OF LONDON, ENGLAND, ASSIGNOR OF ONE-HALF TO CHARLES KNIGHT & COMPANY, LIMITED, OF LONDON, ENGLAND.

MEANS FOR SECURING BOOKS IN DETACHABLE COVERS.

Application filed August 23, 1921. Serial No. 494,501.

(GRANTED UNDER THE PROVISIONS OF THE ACT OF MARCH 3, 1921, 41 STAT. L., 1313.)

To all whom it may concern:

Be it known that I, JAMES SAMUEL KING, a subject of the King of Great Britain, residing at 227-239 Tooley Street, London, England, have invented new and useful Improvements in Means for Securing Books in Detachable Covers (for which I have filed applications in Great Britain on March 20, 1919, Patent No. 136,738 of 1919, and on June 23, 1920, Patent No. 157,689 of 1920), of which the following is a specification.

This invention relates to improved means for securing books in detachable covers, such as are commonly employed to protect ledgers and other books when in use and to obviate the necessity of providing the books with strong permanent bindings.

Preferably I cut the front of the cover of the book along two lines in its upper half parallel to its front edge so that one of the straps may be passed through the loop so formed, and I make similar cuts in the lower half so that the other strap may be passed through the loop so formed. In both cases slits at right angles to the cuts may be made in the cover to receive flaps formed on the straps. The back cover of the book is similarly cut to receive the two other straps.

My invention is illustrated in the accompanying drawing. Figure 1 is a plan of a book with the front board of the detachable cover opened, Figure 2 shows a plan of a portion of the detachable cover and Figure 3 a plan of a portion of the front permanent cover of the book when the straps are secured to the back. Figure 4 shows part of the inside of the front permanent cover of a book secured to the front board of a detachable cover, and Figure 5 is a similar view showing the parts before the permanent cover is secured, the straps being secured to the top and bottom edges of the detachable cover.

In Figures 1 to 3 *a* is the front board of a detachable cover and *b* is the front board of the permanent cover of a book. *c c* are straps fastened to the back of the detachable permanent cover and *d d* are cuts made through the permanent cover *b* parallel to its back forming loops *e e* through which

the straps *c* may be passed, as shown in Figure 1. The end of each strap *c* is cut away so as to form flaps *f f*, *g g*, and slits *h h*, *j j* are formed in the permanent cover of the book through which the flaps *f f* and *g g* respectively are passed. The back board is similarly provided with straps by means of which the back of the permanent cover can be secured to it.

In Figures 4 and 5 *A* is the front board of a detachable cover and *B* is the front of the permanent cover of a book. *C* is a strap secured to the top of the inside of the board *A* and *D* is a similar strap secured to the bottom thereof. *E E* are cuts made through the permanent cover *B* parallel to the top and bottom edges thereof, forming loops *F* and *G* through which the straps *C* and *D* can be passed. The end of the strap *C* is cut away so as to form two flaps *H H*, one on either side, and the end of the strap *D* has formed in it two slits *I* so that when the strap *D* has been passed through the loop *G* and the strap *C* through the loop *F* so that the end of the strap *C* lies above the end of the strap *D*, the flaps *H* may be tucked in through the slits *I*. Pockets *J* at the corners of the board *A* receive the corners of the permanent cover *B*.

The back board of the detachable cover is similarly provided with straps *C* and *D* by means of which the back of the permanent cover of the book can be secured to it.

What I claim is:—

1. The combination of a book having a permanent cover, a detachable cover therefor, straps secured to the detachable cover and loops on the permanent cover of the book through which the straps pass.

2. The combination of a book having a permanent cover, a detachable cover therefor, four straps secured to the detachable cover two on each side thereof and four loops on the permanent cover of the book extending parallel to the edges through which the straps pass.

3. The combination of a book having a permanent cover, a detachable cover therefor, four straps secured to the detachable cover and four loops on the permanent cover of the book through which the straps pass,

two loops being in the upper half of each part of the permanent cover and two loops in the lower half of each part thereof.

4. The combination of a book having a permanent cover, a detachable cover therefor, straps secured to the detachable cover flaps on each strap and cuts in the permanent cover of the book extending parallel to the front edges through which the straps

10 pass and adapted to receive the flaps.

5. The combination of a book having a permanent cover, a detachable cover therefor, straps secured to the detachable cover, cuts in the permanent cover of the book 15 extending parallel to the front edges

through which the straps pass, flaps on the straps and slits at right angles to the cuts to receive the flaps.

6. The combination of a book having a permanent cover, a detachable cover therefor, straps on the detachable cover and means for securing the straps in such a position that they hold the back and front of the permanent cover to the back and front of the detachable cover.

In testimony that I claim the foregoing as my invention I have signed my name this eighth day of August 1921.

JAMES SAMUEL KING.
